(57) **CLAIM**

The ornamental design for a toilet detection plate, as shown and described.

DESCRIPTION

FIG. 1 is a front, top perspective view of a toilet detection plate showing my new design.

FIG. 2 is a front, bottom perspective view thereof.

FIG. 3 is a top plan view thereof.

FIG. 4 is a bottom plan view thereof.

FIG. 5 is a front elevational view thereof, the rear elevational view being a mirror.

FIG. 6 is a right side elevational view thereof, the left side elevational view being a mirror image; and,

FIG. 7 is a sectional side elevational view taken along line 7-7 in FIG. 3.

The broken lines represent portions of the toilet detection plate that form no part of the claimed design.

1 Claim, 3 Drawing Sheets
